UNITED STATES PATENT OFFICE.

WILLIAM REGAN, OF BRANFORD, CONNECTICUT, ASSIGNOR TO THE BRANFORD LOCK WORKS, OF SAME PLACE.

ATTACHING KNOBS TO SPINDLES.

SPECIFICATION forming part of Letters Patent No. 325,445, dated September 1, 1885.

Application filed July 27, 1885. (No model.)

To all whom it may concern:

Be it known that I, WILLIAM REGAN, of Branford, in the county of New Haven and State of Connecticut, have invented a new Improvement 5 in Attaching Knobs to Spindles; and I do hereby declare the following, when taken in connection with accompanying drawings, and the letters of reference marked thereon to be a full, clear, and exact description of the 10 same, and which said drawings constitute part of this specification, and represent, in—

Figure 1, a side view of the knob, showing a longitudinal section of the neck, the rose, and the nut; Fig. 2, a perspective view of the 15 nut, showing the flange; Fig. 3, a perspective view of the neck, showing the shoulder; Fig. 4, a rear view of the rose; Fig. 5, a modification, showing the nut as secured to the door independent of the rose.

20 This invention relates to a device for adjusting door-knobs upon their spindles, so as to adapt them to doors of differing thickness, and is an improvement on the invention for which Letters Patent were granted to me March 25, 1877, No. 188,946, and which consisted in constructing the neck of the knob with an annular groove near its inner end, and combining therewith a nut with lugs to enter the 30 said groove, and threaded axially with the opening of the neck of the knob, to correspond to the thread on the angles of the knob-spindle, the said nut holding the knob at any point on the spindle to which the said nut may be turned, and with the rose constructed to 35 prevent the nut turning with the spindle.

In that invention it is necessary to attach the knob with the rose to the nut before engaging the nut with the spindle, thus necessitating the drawing of the knob and rose for a 40 considerable distance upon the spindle by means of the nut—quite a difficult operation.

45 My object is to avoid this difficulty; and it consists in constructing the inner end of the neck of the knob with a shoulder extending partially around it, and the nut adapted to screw upon the spindle, with a concentric grooved flange partially around the outer face and adapted to engage the shoulder on the knob, as more fully hereinafter described.

50 A is the spindle, of usual form, screw-

threaded upon its angles. B is the knob, constructed with a neck, C, the said neck constructed with an angular longitudinal hole corresponding to the shape of the spindle, and with a shoulder, *a*, at its inner end, extending 55 preferably about half around the neck, as shown in Fig. 3.

D is the nut, internally screw-threaded to correspond with the thread upon the angle of the spindle, and constructed with a concentric 60 grooved flange, *b*, preferably semicircular, as shown in Fig. 2, and adapted to engage the shoulder *a* on the neck of the knob, for the purpose of holding it in any desired position. *d* is an ear upon the edge of the nut. 65

E is the rose, constructed with notches *e e*, to engage the ear *d*, to hold the nut in position.

To secure the knob to the spindle, screw the nut upon the spindle until it is nearly to a bearing against the door, place the knob and 70 rose upon the spindle against the nut, and so that the shoulder on the neck will pass the flange on the nut, and then turn the nut to a bearing, which will cause the flange *b* to pass over the shoulder *a*. The nut is secured by 75 engaging the ear *d* with one of the notches *e e*, then securing the rose to the door in the usual manner. The nut may be secured directly to the door by a screw through the edge of the nut, as seen in Fig. 5. In this case I have 80 shown the shoulder *a* and the flange *b* to extend one-half of the circumference of the neck and nut; but they may be of any desired length, it only being essential that the nut should be adapted to engage the neck after the nut is 85 screwed upon the spindle.

I claim—

1. The combination of the angular spindle A, screw-threaded upon its angles, the knob B, with its neck C constructed with an angular 90 longitudinal hole corresponding to the spindle, and with a shoulder, *a*, extending partially around the inner end, and a nut, D, internally screw-threaded to correspond to the thread upon the angles of the spindle, and 95 constructed with a concentric grooved flange, *b*, to engage the shoulder *a* on the neck, and adapted to be secured to the door, substantially as described.

2. The combination of the angular spindle 100

A, screw-threaded upon its angles, the knob B, with its neck C constructed with an angular longitudinal hole corresponding to the spindle, and with a shoulder, *a*, extending partially around its inner end, a nut, D, internally screw-threaded to correspond to the thread upon the angles of the spindle, and constructed with a concentric grooved flange, *b*,

to engage the shoulder *a* on the neck, and with an ear, *d*, upon its edge, with a rose constructed with notches *e*, to engage the ear *d*, substantially as and for the purpose described.

WM. REGAN.
